Primary Examiner — Sandra S Snapp*Assistant Examiner* — Katherine Glennon(74) *Attorney, Agent, or Firm* — Brinks Gilson & Lione;
John C. Freeman(57) **CLAIM**

The ornamental design for a watch case with strap, as shown and described.

DESCRIPTION

FIG. 1 is a top view of a watch case with strap according to the present invention;

FIG. 2 is a bottom view;

FIG. 3 is a front view thereof;

FIG. 4 is a right side view thereof;

FIG. 5 is a top perspective view thereof;

FIG. 6 is a bottom perspective view thereof;

FIG. 7 is a top perspective exploded view thereof; and,

FIG. 8 is a bottom perspective exploded view thereof.

The ornamental design which is claimed is shown in solid lines in the drawings. The broken lines showing of portions of the article form no part of the claimed design.

1 Claim, 8 Drawing Sheets(56)
